EX

John Rogers

Dec. 1558

In the Register of Patents of New York, N. Y.
Letters Patent No. 1558, dated April 1, 1862.

The following is contained in these Letters Patent and constitutes part of the same.

To all whom it may concern:

It is known that I, John Rogers, of the City and County of New York and State of New York, have invented or produced a new and original design for a group of figures, and I do hereby declare that the following is a full and exact description of the same, reference being had to the accompanying drawing.

The group consists of three figures and is called the
The Picket Guard.

The central one A, is an officer and on either side of him is a soldier, B. C. in Zouave costume. They are supposed to have just discovered the enemy. The soldier B, is in the act of cocking his gun D. The officer A, restrains him from firing with his right hand E, and grasps his sword F, with his left hand G. The soldier C, holds his gun H, in his right hand I, and shades his eyes with his left K, while he gazes eagerly towards the enemy.

The three figures are standing and the officer A, a trifle in advance of his companions.

Having thus described my invention, what I claim and desire to secure by Letters Patent, is the design for a group of statuary as herein fully described and shown.

Witnesses,

J. Q. A. Ward, }
James, N. G. Bart. }
